UNITED STATES PATENT OFFICE

KENLY C. BUGG, OF ST. LOUIS, MISSOURI

POLISHING MACHINE

Application filed August 10, 1929. Serial No. 385,009.

This invention relates to polishing machines.

An object of the invention is to provide a portable polishing machine comprising a rotary support for the polishing members, in combination with devices for pressing the polishing members yieldingly against the surfaces to be polished automatically and as an incident to the operation of the machine and irrespective of the shape or form of the surfaces.

Another object is to provide means in connection with the machine of my application Serial No. 368,787, filed June 6, 1929, for pressing the wipers against plane or irregular surfaces.

Other objects will appear from the following description, reference being made to the accompanying drawing in which—

20 Fig. 1 is a vertical sectional view of the housing of my improved machine, the operative mechanism being shown in elevation.

Fig. 2 is a plan view of the machine.

25 Fig. 3 is a horizontal sectional view approximately on the line 3—3 of Fig. 1.

Fig. 4 is a sectional view approximately on the line 4—5 of Fig. 1, showing the wipers pressed against an outwardly rounded or ovolo surface.

30 Fig. 5 is a similar sectional view on the line 4—5 of Fig. 1 showing the wipers pressed into a groove.

Fig. 6 is a plan view and a side elevation view of the presser device for the wipers.

35 Fig. 7 is a plan view and a side elevation view of one of the wipers.

The polishing device is confined within a housing comprising two end walls 1 and 2 and a curved wall 3 having its marginal edges 40 attached to the walls 1 and 2 and cooperating therewith to form an enclosure which is open on one side. The marginal edges of the walls 1, 2 and 3 are rolled to form a bead 4 and this bead is enclosed by a strip of non-abrasive 45 fibrous material 5. One edge of this strip 5 lies against and is secured to the inner marginal portions of the walls 1, 2 and 3, and the outer portions of said strip is folded to 50 enclose the bead 4 and to lie against the outer side of said walls 1, 2 and 3. The marginal

portion of said strip 4 is clamped against the walls 1, 2 and 3 by a band 6 surrounding the walls 1, 2 and 3 above the bead 4. Thus a protected edge for the housing is provided so that the housing may be moved along the 55 smooth surface that is to be polished by the polishing machine without scratching or marring said surface.

A suitable motor 7 is supported by the wall 2 and is energized by any appropriate circuit connections and controlling switches, which matters are well within the skill of the mechanic and, therefore, are not shown in the drawings. The motor shaft 8 is supported for operation approximately parallel with the 60 surface to be polished and projects through the wall 2, across the space between the walls 2 and 1 and has its outer end journaled for rotation in a bearing 9 in connection with the wall 1. A frame for supporting the polishing wipers is attached to the shaft 8 within the housing. This frame comprises a hub block 10 rigid on the shaft 8 and having attached thereto a number of arms 11.

65 A non-metallic fibrous wiper and a presser device therefor is attached to each of the frame arms 11 by clamping screw bolts 12. These screw bolts pass through the inner marginal edges of the respective wipers and through the supports for the presser devices and through the frame arms 11, which are overlapped by said wipers and said presser device supports, as shown in Fig. 1. Each wiper comprises a fibrous body or sheet 13 secured to the corresponding frame 11, as 70 described, and having its outer portion split to form fibrous arms 14, which are disconnected and are in abutting contact throughout their length. The actuators or pressers for these wiper arms 14 comprise spring arms 75 15 pressing against the rear sides of the wiper arms 14 and formed in connection with a supporting plate 16 interposed between the fibrous sheet 13 and the adjacent arm 11 of the supporting frame. These spring arms 80 15 are of less width and less length than the width and length of the corresponding wiper arms 14 so that there is never any opportunity for these metallic spring arms to contact 85 with the surface being polished. This con- 90 95 100

struction, including the separated fibrous wiper arms 14 and the independent presser devices 15 therefor, permits the machine to be used with entire satisfaction in polishing surfaces of a wide variety of shapes and contours. For, by reference to the drawing, it is clear enough that the machine may be used with a high degree of satisfaction in polishing plane surfaces or in polishing outwardly rounded or ovolu surfaces, as shown in Fig. 4, or in polishing the inwardly rounded, grooved or ogee surface of Fig. 5. Approximately equal pressure is applied to all of the wiper arms so that said wiper arms operate with approximately equal pressure against all of the portions of these plane or rounded surfaces.

The outer edges of the respective arms 11 and the overlapping portion 13 of the wipers 20 are braced and strengthened by frame members 17 having their ends attached to the outer ends of the respective frame arms 11 by removable screw bolts 15. As shown, one end of each frame member 17 abuts against 25 the forward side of an adjacent frame arm 11 and the opposite end of said frame member 17 is clamped against the wiper sheet 13 that is attached to the next following frame arm 11.

As shown, it is essential that the frame members 11 and 17 do not extend to the plane of the edges of the walls 1, 2 and 3, but that the wiper arms 14 and the pressers 15 therefor are of such length that they may extend 35 well beyond the edges of said walls. For, if the frame members 11 and 17 extend to the edges of the walls 1, 2 and 3, the surface of the articles being polished would thereby be scratched and marred during operation of 40 the machine.

Within the housing a block 18 of pumice stone or other appropriate material is secured by a removable fastener 19. This block 18 is in such position that it is slapped by the 45 wiper arms 14 during operation of the machine in order to charge the wipers with minute particles of the stone or the like so that the wipers will constantly operate in the most efficient manner. Sufficient pressure is applied to the wiper arms 14 by the presser arms 15 to cause said wiper arms to operate 50 properly against the block 18. Further, sand paper or other abrasive sheets may be used instead of the fibrous wipers mentioned. To 55 opposite sides of the wall 3 removable handles 20 are attached by fasteners 21. These handles 20 are for manual engagement in moving and operating the machine from place to place and along the surface of the 60 articles to be polished.

In using this device the motor 7 is kept in constant operation, thereby operating the polishing device in the direction indicated by the arrow 22 in Fig. 1. The machine is 65 supported on or against the surface of the ar-

5 ticle to be polished, the non-abrasive surface 4 of the housing sliding along said surface. The motor rotates the frame within the housing in the direction indicated by the arrows 22, causing the polishing arms 14 to contact with and rub and wipe the surface to be polished, sufficient pressure being applied against said polishing arms 13 by the springs 15. The machine is easily manipulated and moved from place to place and in operation. It is clear that the machine obtains all of its intended objects and purposes in a highly efficient and satisfactory manner.

The construction and arrangement of the elements of this machine may be varied within equivalent limits without departure from the nature and principle thereof.

I claim:

1. A device of the character described comprising two spaced end walls having aligned supporting edges, a curved wall attached to said end walls and cooperating therewith to form an enclosure which is open at the side along which said supporting edges of said end walls extend, non-abrasive elements in connection with said supporting edges of said end walls, a rotary shaft supported by said end walls, a motor supported by one of said end walls for rotating said shaft, a frame attached to said shaft within said enclosure, and a series of wipers attached to and having wiping portions projecting beyond said frame and arranged to wipe against a surface along which the device is moved and on which the device is supported by said non-abrasive material.

2. A device of the character described comprising a pair of spaced end walls, a curved wall attached to said end walls and cooperating therewith to form an enclosure which is open at one side, non-abrasive material in connection with the edges of said walls at the open side of said enclosure for supporting said enclosure on a surface to be polished, a motor supported by one of said end walls, a motor shaft projecting from and adapted to be rotated by said motor and extending through said enclosure, a frame attached to said shaft within said enclosure, and a series of wipers attached to said frame and having wiping portions projecting beyond said frame and arranged to operate against and along the surface to be polished when said housing is moved along said surface and said frame is rotated.

3. A device of the character described comprising walls forming a housing and having an open side, non-abrasive material in connection with the edges of said walls at the open side of said housing for supporting the housing on a surface to be polished, a motor supported by one of the walls of said housing, a shaft rotated by and projecting from the motor through said housing, a frame attached to said shaft within said housing, wipers

attached to and having wiping portions projecting beyond said frame and arranged to operate against and along the surface to be polished when said frame is rotated, a device supported within said housing for impregnating said wipers with an abrading substance automatically and as an incident to the rotation of said frame, and resilient means supported by said frame for pressing said wipers against said impregnating means.
